UNITED STATES PATENT OFFICE.

CHANNING L. SMITH, OF DES MOINES, IOWA.

METHOD OF CUTTING KEYS.

1,254,442.

Specification of Letters Patent. Patented Jan. 22, 1912.

Application filed October 16, 1910. Serial No. 125,822.

To all whom it may concern:

Be it known that I, CHANNING L. SMITH, a citizen of the United States, and a resident of Des Moines, in the county of Polk and State of Iowa, have invented a certain new and useful Method of Cutting Keys, of which the following is a specification.

The object of my invention is to provide a simple and effective method of cutting keys from blanks.

A further object of my invention is to provide such a method and a device for employing said method so constructed and arranged as to be used in connection with a lock of the tumbler type, so that notches may be cut in a blank key quickly and accurately for fitting the particular lock desired.

Still a further object is to provide such a device so constructed and arranged that the notches may be accurately cut and entirely finished at one operation without fitting and trying the key.

My invention consists in the method hereinafter set forth in the construction, arrangement and combination of the various parts of the device whereby the objects contemplated are attained, as hereinafter more fully set forth, pointed out in my claims and illustrated in the accompanying drawings, in which:

Figure 1 shows a top or plan view of a key cutting machine embodying my invention.

Fig. 2 shows a front elevation of the same.

Fig. 3 shows a front elevation of my machine in another of its operative positions.

Fig. 4 shows an end or side elevation of a modified form of the machine, the dotted lines showing the movable frame in its raised position.

Fig. 5 shows a top or plan view of the mechanism for holding the tumbler cylinder of a lock.

Fig. 6 shows a vertical, sectional view, taken on the line 6-6 of Fig. 5.

Fig. 7 shows a vertical, sectional view through the key cylinder, taken on the line 7-7 of Fig. 5, with a blank key installed therein.

Fig. 8 shows a vertical, central, sectional view through the key cylinder with a finished key therein, and

Fig. 9 shows a transverse, sectional view

through the clamp device for the blank key which is to be cut.

In the accompanying drawings, I have used the reference numeral 10 to indicate generally the supporting base for the parts of my improved key cutting machine.

On one end of said base is an upwardly extending block 11, shown in Fig. 9.

Slidably mounted on the base 10 and adapted to slide fore-and-aft thereon toward and from one side of the block 11 is a clamp member 12. Rotatably but non-slidably mounted in the clamp member 12 is a shank 13 of a screw 14. The screw-threaded portion of said screw 13 is extended into the block 11. Cut in the upper surface of the block 11, along one edge thereof, is a rabbit or notch 15. Formed on the clamp member 12 is a projecting flange 16 adapted to project into the notch 15 when the clamp member 12 is moved toward the block 11.

In the construction as shown, the clamping or vise device, just described, is located at the front of the machine at the left-hand side thereof, and the parts are so arranged as to clamp a key 17 in the notch 15 between the flange 16 and the block 11 in such manner that the key is arranged transversely of the machine, as shown in Figs. 1 to 3.

The surfaces of the block 11 and the clamp member 12, at their left-hand ends, are flush with each other.

Mounted on the base 10, preferably near the right-hand side thereof, and near the forward end thereof, opposite the clamping device already described, is a second clamping device comprising an upwardly extending block member 18 on the opposite sides of which are slideable clamp members 19 and 20.

Rotatably but non-slidably mounted in the block 18 is a screw 21, having on its shank 22 on opposite sides of its neutral portion, right and left-handed screw threads 23 and 24, arranged to coact with corresponding screw-threads in the sliding clamp members 19 and 20.

On the outer end of the screw 21 is a head 24.

The clamp members 19 and 20 are opposite slots 25 adapted to receive the annular flange on the end of the tumbler cylinder 100 of a lock.

There are preferably extended through the clamp members 19 and 20, suitable guide rods 26, one of which is shown partly in full and partly in dotted lines in the upper 5 part of Fig. 5, and the other part is shown by dotted lines in the lower part of said Fig. 5.

In this connection it may be mentioned that my device is especially adapted for use 10 in cutting keys for tumbler locks such as the well known "Yale lock."

At the rear end of the base 10 are upwardly extending bearing members 27 in which the transverse shaft 28 is mounted.

15 Supported on the shaft 28 are the arms 29 of a forwardly extending bracket which in the form of the device shown, are connected at their forward ends.

20 Formed on the forward end of the bracket, just mentioned, are forwardly extending horizontal spaced bearing members 30, in which is rotatably mounted a shaft 31, on one end of which is a crank wheel 32 or other means for imparting rotation to the 25 shaft 31.

In the central portion of the pivoted bracket, now being described, is mounted a screw 33, which when the bracket is in horizontal position, extends downwardly and is 30 adapted to be manipulated to contact with the base 10 for limiting the forward movement of said bracket.

25 A spring is provided for yieldably supporting the frame member 29, comprising two spaced coils 34 mounted on the shaft 28.

30 A U-shaped connecting member 35 is connected with each of the coils 34 and is designed to rest on the base 10, as shown in Fig. 4. The opposite ends 36 of the respective coils 34 are extended forwardly in the machine and are provided with lateral extensions 37 resting beneath the arms of the frame 29, as shown in Figs. 1 and 4. The 40 parts are so arranged that the weight of the frame 29 and the parts carried thereby, when the frame 29 is in horizontal position, will compress the spring and permit the mechanism supported by the forward part of the frame on the shaft 31 to swing downwardly 45 until the screw 33 engages the base 10.

When, however, the frame 29 is tilted upwardly to its position shown by dotted lines in Fig. 4, thereby considerably shifting the center of gravity of said frame, the 50 spring will hold the frame in its raised position.

A stop 38 limits the upward and rearward swinging movement of the frame 29, Fig. 4.

60 The shaft 31, when the frame 29 is in its horizontal position, rests directly over the clamp device hereinbefore described.

On the end of the shaft 31 opposite the crank wheel 32 is a cutting disk or wheel 39. 65 Mounted in the forward portion of the

frame 29, on which the bearings 30 are formed, is an upright member 40 capable of vertical adjustment and having at its lower end a forwardly extending arm 41 adapted to stand above the clamp members 19 and 20. 70

A set-screw 42 is mounted in the forward portion of the frame 29 and is adapted to serve for locking the upright member 40 in any of its adjusted positions.

I shall now describe the practical operation of my key cutting machine. 75

In preparing to cut the notches in a key to make that key fit any particular lock of the tumbler type, I remove the cylinder 43, which carries the tumblers, from the lock. 80 This cylinder has at one end an annular flange 44, as clearly shown in Figs. 7 and 8.

The cylinder 43 has a key hole. Mounted in the wall of the cylinder are a series of 85 tumblers.

In Figs. 7 and 8, are shown three of the tumblers, indicated by the characters 45, 46 and 47. The cylinders 43, which are herein mentioned are of the very common type, which are used in a large per cent of the 90 Yale and Corbin locks of today. These locks are constructed to receive a cylinder such as is shown at 43 herein, this cylinder being rotatably mounted transversely of the lock. The outer end of the cylinder has the 95 flange 44 thereon and an opening therein adapted to receive a key. The key projects through said opening and into the cylinder, which is provided with a longitudinal slot, which receives the notched end of the key 100 and which is made in various shapes in cross section.

Above the last described slot is a row of equi-distant openings adapted to slidably receive pointed pins 45, 46 and 47. These 105 pins are of such length that when the lower pointed ends have fallen to fit into the adjacent notches of the key, which belongs to that lock, the upper ends of said pins will be flush with the outer surface of the cylinder as shown in Fig. 8. The lock frame further supports a row of slidably mounted vertical pins, which correspond in diameter and position to the pins 45, 46 and 47. The last described pins are placed directly above 110 the cylinder 43 and their lower ends are pushed downwardly against the upper surface of said cylinder by means of springs or the like. The cylinder 43 is so arranged that when the pins 45, 46 and 47 are directly 115 beneath the second described set of pins the bolt or latch will be in its locked position. It will be seen by referring to Fig. 8 that if the key 48 should be withdrawn from the lock the pins 45, 46 and 47 would be allowed to fall down farther into the key slot in said cylinder. As soon as these pins so fall it will be seen that the pins of the second described row would immediately fall down so that the lower ends of the second 120

85

110

115

120

125

130

described pins would enter the upper part of the openings in which the first described pins reciprocate. When the second described pin thus enters the opening in cylinder 43 they lock it in place thereby preventing the cylinder from being turned and the latch or bolt moved thereby.

If it is desired to unlock the lock, the key 48 is inserted in the key slot thereby moving pins 45, 46 and 47 so that their upper ends are flush with the surface of the cylinder and will thereby push the second described pins upwardly so that their lower surfaces are also flush with the surface of the cylinder. As the contacting ends of both sets of pins are thus flush with the surface of the cylinder, said cylinder may be rotated by turning the key thereby moving the latch or bolt to unlocked position.

Assuming that the cylinder 43 has been removed from the lock, I then insert the shank of a blank key 50 into the key hole slot 43^a, as shown in Fig. 7. It will be seen that the tumblers 45, 46 and 47 will be forced outwardly. The length of those portions of the tumblers just described projecting away from the cylinder 43 is exactly the same as the proper depth for cutting the notches in the key blank, so that the tumblers can drop into said notches until their outer ends are flush with the outer surface of the cylinder 43.

With the frame 29 raised, I clamp the cylinder 43 between the members 19 and 20 with the flange 44 received in the notches 25, and abutting against the bodies of the members 19 and 20 at the right-hand side of said notches, as shown in Figs. 5 and 2.

Another similar blank key 17, shown in Figs. 2, 3 and 9, is clamped between the members 12 and 11 resting against the shoulder formed by the notch 15.

Key blanks of this type are provided with opposite lugs or ears 51 adjacent to the handle of the key. In preparing the key blanks for cutting the notches, I cause the lugs 51 to abut against the flange 44 and against the clamp members 12 and 11, respectively.

The frame 29 is then lowered and the upright 49 is adjusted to position where the arm 41 thereon rests upon the upper end of the tumbler 45, and the cutting disk 39 rests upon the upper surface of the blank key 17, as shown in Fig. 2.

The frame 29 is capable of sliding movement with relation to the base 10, and is preferably arranged to slide on the shaft 28.

The parts of the machine are so arranged that after they have been adjusted, as above described, and the frame 29 is shifted to the right a sufficient distance, the arm 41 is permitted to clear the tumbler 45 and stands between the tumblers 45 and 46.

The cutting disk 39 stands in proper po-

sition above the key blank 17 for cutting the first notch therein. The crank wheel is then rotated for cutting the notch in the key blank 17, and as the disk travels downwardly in cutting a notch, the arm 41 drops into the space between the tumblers 45 and 46, as shown in Fig. 3.

It will be noted that the depth of the notch is determined by the possible downward limited movement of the forward part of the frame 29. This downward movement is limited by the arm 41, which engages the cylinder 43, whereby the depth of the notch cut equals the length of that portion of the tumbler 45 projecting out of the cylinder 43.

The first notch made in the key blank 17, will have been cut at such a point as to properly receive the tumbler 45 when the forward key is inserted into the cylinder 43, as illustrated in Fig. 3.

The frame 29 is then raised slightly and moved farther to the right, and the arm 41 is adjusted to rest on the outer end of the tumbler 46, while the cutting disk 39 rests upon the upper edge of the partly finished key 17.

The frame 29 is then again moved to the right until the arm 41 rests above the space between the tumblers 46 and 47, whereupon the disk 39 will be in proper position for cutting the second notch in the key.

The crank wheel is rotated for cutting the second notch and the parts are then adjusted and a third notch is completed.

The movable member 29 is then raised and will be held in its raised position by the spring hereinbefore described.

The key 17 can be removed and the cylinder 43 can be taken out of the machine and the key blank 50 removed therefrom, and it will be found that notches have been cut in the key 17 in exactly the proper positions, so that when the key 17 is inserted into the cylinder, the outer ends of the tumbler therein will stand flush with the outer surface of the cylinder.

It will be seen that with a machine of this description a key can be cut to fit a lock in a very short time, and that the notches may be made with great accuracy.

The advantages of a machine of this type as compared with the old method of filing and cutting the key and fitting it by constant trials, are obvious.

Some changes may be made in the details of the practice of my method without departing from the essential features and purposes thereof, and it is my intention to cover by this application, and the patent to be issued thereon, any such modification of structure or use of mechanical equivalents, which may be reasonably included within the scope of my claim.

I claim as my invention,

The method of duplicating keys for locks

of the type which have a rotatable cylinder therein adapted to be secured in locked position by a row of pins mounted to slide into and out of said cylinder, consisting of first 5 removing said cylinder with its tumbler pins from the lock, then placing a key blank in the key hole of the cylinder whereby the tumbler pins will be forced outwardly from

the cylinder a distance equal to the depth of the notches in a key adapted to fit the lock, then cutting notches in a second key blank by a cutter controlled in its operation by said tumbler pins as a pattern.

Des Moines, Iowa, September 18, 1916.

CHANNING L. SMITH.
